UNITED STATES PATENT OFFICE

EDMUND J. TE PAS, OF LAKWOOD, OHIO, ASSIGNOR TO THE CLEVELAND HEATER COMPANY, OF CLEVELAND, OHIO, A CORPORATION OF OHIO

WATER HEATER

Original application filed July 20, 1926, Serial No. 123,690. Divided and this application filed April 21, 1928. Serial No. 271,725.

This application is a division of copending application Serial No. 123,690, which has matured into Patent No. 1,759,891, filed July 20, 1926 by Walter W. Ziegler, Loran F. Doen and Edmund J. Te Pas as joint inventors and relates to improvements in the base and burner construction of fluid fuel fired water heaters.

It is customary in water heaters of the usual type, in which a tank of water is heated by the flame from a gas burner positioned below water circulation elements in communication with the tank, to mount the burner upon a Bunsen or mixing tube by either a ground or a threaded joint.

When a ground joint is used, the end of the Bunsen tube is finished smooth and slightly tapered and adapted to snugly fit into a bored out cylindrical extension of the burner. This type of joint is open to the objection that upon removal and replacement of the burner a gas-tight fit may not be achieved on account of dirt or other foreign material lodging between the contacting portions of the Bunsen tube and burner.

In order to overcome this objection and still retain advantages of the ground joint, such as ease in removal and replacement of the burner for cleaning etc., heaters have been made in which the Bunsen tube and burner are provided with a threaded joint to insure at all times a gas-tight connection at this point.

Experience has shown that after a time the threaded joint becomes rusted and it is impossible to remove the burner from the Bunsen tube without the use of tools which cannot be manipulated in the limited space in the heater casing. In this case the heater base which carries the Bunsen tube and burner is removed from its casing and the burner is then removed from the Bunsen tube.

One of the objects of this invention is to provide a heater base in which the assembled burner and Bunsen tube can be quickly and easily installed or removed without disturbing the attachment of the base to the heater casing.

Another object of this invention is to provide an improved means of connecting the Bunsen tube to the gas feed line. These and

other objects will appear from the following detailed description and appended claims.

In the accompanying drawings forming a part of this specification are illustrated embodiments of the features of this invention in which: Fig. 1 is an elevation partly in section of a water heater with a section of its base removed and embodying features of this invention. Fig. 2 is an elevation of the Bunsen or mixing tube. Fig. 3 is a perspective view of the heater base member used in Fig. 1.

Referring to Fig. 1, the numeral 1, designates the casing of a heater having a heating coil 2 adapted to be connected at its extremities in the usual manner to the top and bottom of a boiler, so that there is a circulation of water through the coil and boiler when the burner 3 is in operation. The burner 3 is mounted on a Bunsen or mixing tube 4 by means of a threaded joint.

Means comprising projecting lugs 5 and a collar 6 forming an integral part of the Bunsen tube cooperating with helical projections or ledges 7 in a central aperture 9 of the base 8 to securely and detachably hold the Bunsen tube in position in the heater base. A pair of diametrically opposed vertical slots 10 for reception of the lugs 5 permit the insertion and removal of the Bunsen tube in the assembled heater base.

The heater base 8 is made in two pieces comprising the fixed element 11 and the removable element 12 shown in Fig. 3 and is provided with skirted portions 13 and a recessed portion at 14 to form a drip collection and evaporation pan for condensates from the heating coils. A raised seat 15 having positioning lugs 16 is adapted to be detachably held in contact with the heater casing by rods or bolts passing through the holes 17 formed in the base.

Secondary combustion-supporting air inlets 18 are provided between the drip pan and the skirted edge of the base. In order to permit the insertion or removal of the burner and Bunsen tube in their assembled state, the removable segment 12 fits in a vertically walled space of similar outline in the base member 11. The removable segment 12 has

vertical walls 19 and recessed portion 14 constituting a drip collection and evaporation pan.

The removable section 12 is provided with 5 overhanging edges 20 adapted to extend over the vertical walls 21 of the fixed member 11 of the heater base. A pair of supporting lugs 22 integrally formed on the fixed member 11 are adapted to fit under the raised seat 15 to 10 support and position the outer edge of the removable section 12. The vertical walls 21 are provided with raised portions 23 to support the inner end of the removable segment 12 of the base. The side walls 19 and over- 15 hanging edges 20 terminate at the inner end of the removable segment 12 in a pair of inclined faces or walls 28 which lie closely adjacent to and in parallel relation with the inclined faces 27 of the fixed portion of the 20 base when the removable section 12 is in position in the fixed section 11.

It is apparent from the foregoing, taken in connection with Figure 3 that the removable section 12 can be easily and readily removed 25 and replaced without the use of tools.

As a further means of facilitating the removal and replacement of the burner assembly, a combined union and spud holder 31 is screwed into the lower end of the Bunsen tube 4. The lower end of this union carries a gas cock 29 to control the flow of gas from a main fuel feed line to the burner. The male element of the union 31 is held from turning in the Bunsen tube by a locknut 33 35 which also serves to lock the air shutter 34 in position. The union nut 32 serves to hold the union together, and upon loosening it the Bunsen tube may be readily disconnected from the gas line permitting the removal of 40 the Bunsen tube with its associated burner from the heater base in the manner described.

Furthermore, it is to be understood that the particular forms of apparatus shown and described, and the particular procedure set 45 forth, are presented for purposes of explanation and illustration and that the various modifications of said apparatus and procedure can be made without departing from my invention as defined in the appended claims:

50 I claim:

1. A base unit and burner support for a heater casing comprising a fixed element having a segmental cut-out portion adapted to be detachably secured to the heater casing, a 55 removable segment adapted for reception in the cut-out portion of said fixed element and defining an aperture therewith, horizontally extending portions carried by said segment adapted to engage said fixed element at a 60 point closely adjacent to the margin of said aperture, means provided by said fixed element for supporting the outer edge of said segment, and a burner carrying tube adapted to be supported in the aperture between 65 said segment and said fixed element, said

tube having a portion engageable with said segment for rigidly holding said segment in position in said fixed element.

2. A base unit and burner support for a 70 heater casing, comprising a fixed element having a segmental cut-out portion adapted to be detachably secured to the heater casing, a removable segment adapted for reception in the cut-out portion of said fixed element and defining an aperture therewith, over- 75 hanging edges carried by said segment adapted to rest on said fixed element adjacent the center thereof, horizontally projecting lugs formed on said fixed element providing a support for the outer edge of said segment, and a burner carrying tube adapted to be supported in the aperture between said segment and said fixed element, said tube having a lug arranged to engage said segment at a point between the innermost and outermost edges thereof whereby said segment is rigidly and removably secured in said fixed element. 80

3. In a gas fired water heater, a heater casing, a drip pan secured to the bottom thereof 90 having a segmental cut-out portion, a removable recessed segment adapted to fit in the cut-out portion of said pan and to form a central aperture therewith, overhanging edges formed on said segment adapted to 95 extend over the marginal edges of the cut-out portion of said pan and to rest on said pan at points adjacent the center thereof, means provided by said pan for supporting the outer edge of said segment, a burner carrying tube adapted to be received and supported in the aperture between said pan and segment, and a lug formed on said tube arranged to engage the inner end of said segment at a point intermediate the sides thereof whereby the segment is securely held in place in said drip pan. 100

4. A base unit for a heater casing comprising in combination with a heater casing, a 110 fixed element adapted to be removably secured thereto and having a segmental cut-out portion, a removable segmental element providing a central opening with said fixed element, means adjacent the center and outer edge of said fixed element to support and position said removable element, a burner carrying tube adapted to be removably supported in the opening between said segment and said fixed element, and means formed on said tube for engaging said element at a 115 point between said support means whereby said element is removably and rigidly secured to said fixed element. 120

In testimony whereof I affix my signature. 125
EDMUND J. TE PAS.
